UNITED STATES PATENT OFFICE.

OSCAR RUST, OF ITHACA, NEW YORK.

WELL-DRILLING MACHINE.

SPECIFICATION forming part of Letters Patent No. 336,353, dated February 16, 1886.

Application filed November 11, 1885. Serial No. 182,463. (No model.)

To all whom it may concern:

Be it known that I, OSCAR RUST, a citizen of the United States, residing at Ithaca, in the county of Tompkins and State of New York, have invented a new and useful Improvement 5 in Well-Drilling Machines, of which the following is a full, clear, and exact description.

This invention is an improvement in well-drilling machines, and particularly in that class 10 of such machines in which the drill-tool is supported on a rope and raised and lowered by the action of a cam operating on a lever supporting the pulley around which the drill-rope is passed to the rope-drum.

15 The invention consists in certain features of construction and combinations of parts, as will be described.

In the drawings, Figure 1 is a side elevation, Fig. 2 a top plan view, and Fig. 3 a front elevation, of my machine. Fig. 4 is a detail sectional view of one of the shafts and its pulleys. Fig. 5 is a detail perspective view of a part of the framing, the lever and the latch therefor, together with the guide-pulley and its connection. Fig. 6 is a detail view of the bearing; Fig. 7, a similar view of a portion of the mast, and Fig. 8 is a side elevation of the machine on the opposite side from that shown in Fig. 1.

The rope-operating lever A, the cam B, for 30 actuating such lever, and the latch mechanism C C C, for locking said lever out of the path of the cam, may be of ordinary construction, and need no detailed description here. The drive and cam shaft D is journaled at the rear end 35 of the framing, and is provided with a friction-drum, d. This shaft D may be driven in any suitable manner. Alongside of shaft D, I journal the intermediate shaft, E, which has a sprocket-wheel, e, at its outer end. On the 40 shaft E, I key or otherwise secure the pulley F, and a pulley, G, is loosely sleeved on the shaft E alongside of pulley F. This pulley G has a sprocket-wheel, g, formed or secured on one end. The intermediate shaft is geared with 45 the rope-drum H through the medium of a shaft, I, having a sprocket-wheel, j, geared by band J with the wheel e, and also having a spur-pinion, i, meshed with a gear-wheel, h, on the rope-drum. By this construction when 50 the intermediate shaft is revolved by its fixed pulley F gearing with the drive-shaft in the manner presently described, the rope-drum

will be revolved to wind the rope and raise the drill.

The slush-pump sleeve I' is suitably journaled to the framing, usually on the shaft I, and has a sprocket-wheel, i', geared by sprocket-band I' with the sprocket g of pulley G. I provide the shaft I with a ratchet, K, and pawl k, by which the drum may be locked from 55 unwinding or be released to let out the rope, as desired.

A suitable brake, L, is arranged to engage a pulley, l, as the shaft I, and such shaft also has a hand-crank, M, by which it may be 60 turned to tighten the drill-rope.

An idler, N, is supported on one end of a pivoted lever, n, the opposite end of which extends to the front of the machine. By depressing the lever the idler will be raised into contact with the drum d, and pulley F gearing the latter with the drive-shaft and communicating motion to the rope-drum by the connections before described. A similar idler, O, and lever o are arranged in like relation to the drum 70 d and pulley G so the slush-pump spool may be revolved. Each of the idlers, it will be seen, is movable independently of the other, so that the slush-pump spool or the rope-drum 75 may be revolved as desired.

80 It will be noticed that the location of the parts in the relations shown simplifies the construction and enables the spool or the rope-drum to be quickly thrown into or out of gearing.

85 Heretofore when the rope-drum and slush-pump spools have been geared positively with the drive-power the sudden shock incident to the working of inventions of this class and the catching of tools within the well in being raised 90 would frequently break the chains, resulting in the expense and delay required for replacing the broken parts.

95 By the friction-gearing arranged as described the gearing will slip slightly under such jars and strains, preventing the breakage before referred to, and also operating practically as a cushion for the entire well rig, easing the jars and obviating the racking of such rig by the jars specified.

100 It will be noticed that the drum H is supported above the body of the frame-work in struts H', by which arrangement it is set sufficiently far from the guide-pulley P to enable

the rope to move from side to side of the drum to wind the rope properly thereon. In order to strengthen these struts and relieve their fastening-bolts from strain, I prefer to employ 5 the upright braces h' between the struts and the body of the frame-work, as shown most clearly in Fig. 1.

The mast Q is provided with lateral trunnions q , which are supported in open bearings 10 r in brackets R, secured to and projected from the main frame on opposite sides of the mast. By this construction the mast may be easily tilted back or may be removed from the bearings for convenience in transportation or storage. The drill-rope S is passed over a pulley 15 at the top of the mast, down around guide-pulley P and up, and is fastened to the drum H. To give the pulley free play and permit it to follow the direction of the rope in winding on 20 the drum, I prefer to provide such pulley with a clevis or loop, p , connected with a clevis or loop, a , on the lever A by a connecting-link, T, as most clearly shown in Figs. 1 and 5. By 25 this construction a strong connection of the parts is provided, and the pulley may freely follow the direction of the rope, and the latter will be prevented from slipping onto the rim of the pulley and cutting or wearing off by frictional contact.

30 The operation of my invention, except in the particulars above specified, is substantially the same as that of other machines of its class—such, for instance, as shown in my Patents Nos. 257,766 and 257,767, granted May 9, 1882.

35 Having thus described my invention, what I claim as new, and desire to secure by Letters Patent, is—

1. The combination, with the rope-drum and the shaft I, geared therewith, of the slush-pump spool journaled on the shaft I and pulleys connected one with the shaft I and the other with spool thereon, the drive-shaft and gearing whereby motion may be transmitted to either the slush-pump spool, the shaft I, or to both of such parts, substantially as set forth. 40

2. The combination of the drive-shaft having a friction-drum, the intermediate shaft, the rope-drum geared with said shaft, a pulley fixed on the intermediate shaft, a pulley sleeved on such shaft, the slush-pump spool geared 50 with such sleeved pulley, and idlers movable into contact with the friction-drum and the pulleys of the intermediate shaft, substantially as set forth.

3. The rope-drum and the shaft I, geared 55 with such drum, and having ratchet K and brake-pulley l, combined with the pawl k and the brake-lever L, arranged and operating substantially as and for the purposes specified.

4. The combination of the shaft D, the shaft 60 E, having pulleys F and G, the rope-drum and the slush-pump spool geared with the shaft E, and pulley G, of gearing whereby either of pulleys F or G may be geared with the shaft D, all arranged and operating substantially as 65 set forth.

The above specification of my invention signed by me in the presence of two subscribing witnesses.

OSCAR RUST.
